UNITED STATES PATENT OFFICE.

WILLIAM B. EARNSHAW, OF DAYTON, OHIO, ASSIGNOR TO GENERAL MOTORS RESEARCH CORPORATION, OF DAYTON, OHIO, A CORPORATION OF DELAWARE.

INTERNAL-COMBUSTION-ENGINE PISTON.

Application filed October 3, 1923. Serial No. 666,221.

The present invention relates to pistons for internal-combustion engines and more particularly to pistons of the so-called "composite" or "bimetallic" type.

Among the objects of the invention is a light weight piston having the heat characteristics of aluminum or its alloys and the expansion and wear characteristics of cast iron.

10 Another object is to simplify the making and assembly of such pistons.

Further objects and advantages of the present invention will be apparent from the following description, reference being had 15 to the accompanying drawing, wherein a preferred form of embodiment of the present invention is clearly shown.

In the drawing:

Fig. 1 is a view in elevation of the piston with part in vertical section along the axis of the pin bosses.

Fig. 2 is a view similar to Fig. 1 but taken at right angles.

Fig. 3 is a bottom plan view of the piston.

As indicated in the drawings, the piston is composed of two portions, one of which, the head portion 10, is cup-shaped and provided upon its outer periphery with grooves 11 for packing rings and has inside the cup two bosses 12 drilled longitudinally and counter-sunk for screws 13 of which there are also two as indicated in dotted lines in Fig. 3.

35 The other portion of the piston or skirt portion 15 is preferably a cylindrical casting having an inturned flange 16 at its upper end, which flange is provided with a flat upper surface and adapted to fit tightly against the lower edge of the cup-shaped head. Skirt portion 15 is also provided with pin bosses 17 and above these with lugs 18 which are drilled and threaded as at 19 for the reception of screws 13.

40 Skirt portion 15 has its upper outer edge 20 beveled, as indicated, and drilled as at 21, several of these drilled holes being provided although only one is shown. This portion 15 is also provided with a ring

groove 22 in which a ring may be placed 50 for the purpose of retaining the piston pin.

It will be noted that the lower edge of the head portion has in its outer periphery an L-shaped groove 25. This in conjunction with the outer edge of the upper surface of flange 16 forms another ring groove. In this groove there is adapted to be placed 55 an oil scraper ring and the bevel 20 is provided to form an annular groove immediately underneath for the collected oil. From this groove the oil runs to the interior of the piston through holes 21.

The skirt portion 15 is also preferably formed of less diameter longitudinally of the piston pin than at right angles thereto. 60 This may be accomplished by grinding away some of the metal as is indicated at 30.

It is to be understood that while the metals mentioned and form shown are to be preferred, other metals and other forms 70 may be substituted within the scope of the claims which follow.

What I claim is as follows:

1. A two part piston comprising a cup shaped head portion carrying a complete ring groove and having its lower, outer edge forming a part of another ring groove; a skirt portion, the upper end of which completes the last mentioned ring groove and is so formed as to provide a space for collecting oil; piston pin bosses carried by said skirt portion; and two screws extending through said head portion and into said piston pin bosses for fastening said head and skirt portions together. 75

2. A two-part piston comprising a cup-shaped head portion carrying a complete ring groove and having its lower outer edge forming a part of another ring groove; a cylindrical skirt portion of which the upper end completes the last mentioned ring groove and provides a space for collecting oil, means being provided for draining said oil; and means for securing the portions 80 together. 90

In testimony whereof I hereto affix my signature.

WILLIAM B. EARNSHAW.
